UNITED STATES PATENT OFFICE

LLOYD A. SMITH, OF DAVENPORT, IOWA

PRESSING AND STEAMING IRON

Application filed June 25, 1928, Serial No. 288,167. Renewed February 9, 1931.

This invention relates to pressing and steaming devices and more particularly to a portable sad iron of the self contained heating type.

One of the primary objects of the invention is to provide a novel attachment for sad irons for supplying steam thereto, whereby the material being pressed can be steamed simultaneously with said pressing operation.

Another important object of the invention is the provision of a steam generating device connected directly with and forming a part of a sad iron, with means for supplying steam from said generator to the iron and forming the iron, so that the steam supplied thereto will be distributed over the face of the material being pressed.

A further salient object of the invention is the provision of novel means for controlling the flow of the steam to the sad iron and novel means for insuring the delivering of dry steam to the sad iron.

A further object of the invention is the provision of a steam generating device embodying a steam generator chamber of novel form with novel means including electric resistance elements for heating said chamber and novel arranged steam passageways for connecting said chamber with the sad iron.

A still further object of the invention is to provide an improved device of the above character, which will be durable and efficient in use, one which will be simple and easy to manufacture and one which can be placed upon the market at a small cost.

With these and other objects in view, the invention consists in the novel construction, arrangement and formation of parts, as will be hereinafter more specifically described, claimed, and illustrated in the accompanying drawings, in which drawings:

Figure 1 is a side elevation of the improved portable pressing and steam device.

Figure 2 is a transverse section taken on the line 2-2 of Figure 1, looking in the direction of the arrows.

Figure 3 is a transverse section taken on the line 3-3 of Figure 1, looking in the direction of the arrows.

Figure 4 is a top plan view of the improved device.

Figure 5 is a bottom plan view of the improved device showing parts of the sad iron broken away and in section.

Figure 6 is a fragmentary detailed transverse section through a portion of the sad iron, and

Figure 7 is a diagrammatic view of the resistance elements employed.

Referring to the drawings in detail, wherein similar reference characters designate corresponding parts throughout the several views, the letter A generally indicates the improved device, which comprises a sad iron B and a steam generating device C.

The sad iron B is preferably of the self-contained heating type, such as a gas iron or as shown an electric iron which can be of any preferred make or size. This iron includes the usual body 10, lower iron plate 11, and manipulating handle 12.

The upper end of the body 12 at the rear portion thereof carries the usual socket 13 for receiving the plug 14 to which is connected, electric conductor wires 15, which may lead from any suitable source of supply. The iron B contains any preferred type of electric heating or resistance element 16.

According to this invention the iron plate 11 of the iron 10 is provided with a pair of converging passageways 17 which lead from the rear end of the iron toward the front and these passageways meet, as shown in Figure 5 of the drawings at the front end of the iron. The passageways 17 have communicating therewith a plurality of steam outlet ports 18, which open out through the lower face of the iron. It is to be noted that these steam outlet ports 18 do not extend to the rear end of the iron but terminate short thereof leaving relatively long unported portions, for a purpose, which will be later described.

The steam generating device C forms an important feature of the invention together with the means for connecting said steam generator with the iron B.

As shown the steam generating device C comprises a substantially solid body 19, which body has its opposite ends and sides receiving

electric heating elements 20, 21, 22, and 23. These heating elements can be of any preferred nature or type and each preferably consists of a resistance wire wound about a 5 suitable insulating core, such as isinglass.

The entire body, with the exception of the lower wall thereof and the heating elements is encased in a suitable casing of asbestos 24 or other non-heat conducting material, which 10 in turn receives a finishing shell 25.

Branch conductor wires 26 lead from the conductor wires 15 and these branch wires have incorporated in the length thereof a control switch 27 and the branch wires are 15 then connected in any preferred way with the heating elements. It is obvious that by manipulating the switch the flow of current to said heating elements can be controlled.

20 The body 19, which if desired, can be made of cast iron is provided with a steam generating chamber 28 adjacent to one lower end thereof and communicating with the upper end of this chamber is a vertical passageway 29. The upper end of the vertical passageway 29 has threaded into the same a valve body 30 provided at its lower end with a needle valve 31. The needle valve 31 is adapted to fit upon said seat and is slidably 25 mounted in the valve body and is surrounded by a suitable packing gland 32. Communicating with the valve body 30 above the needle valve seat is a water feed pipe which leads from a small water reservoir 34. This water reservoir 34 can be supported by suitable brackets, or as shown, by the pipe or tube 33 alone. The upper end of the reservoir is provided with a filling plug 35 and the tube or pipe 33 can have incorporated therein a small control pet cock 36.

40 Leading upwardly from the steam generating chamber 28 and at an angle thereto toward the opposite side wall is a steam passageway 37 which in turn communicates with a vertical steam passageway 38.

The lower end of the vertical passageway 30 communicates with an upwardly and inwardly inclined passageway 39 and the upper end of this passageway is in turn connected with a cross passageway 40 by means of a relatively short vertical passageway 41. The connection of the passageways 38 and 39 forms a substantial trap 42 for the collection of any water which might be carried with the steam, and the water caught in this trap will be heated by the electric heating elements and in turn converted into steam. The opposite ends of the cross passageways 40 45 have connected therewith steam delivery and supporting pipes 43 which communicate with the covering passageways 17 formed in the iron plate 11.

60 Any preferred means can be provided for operating the needle valve 31 and as shown

I have provided an elongated lever 44 which is pivoted adjacent to its rear end on a supporting bracket 44 carried by the valve body 30.

The extreme rear end of the lever 44 in rear of its pivot point is provided with a slotted yoke 46 which receives the pivot pin 47 carried by the upper end of the needle valve 31. The forward end of the lever is provided with upwardly extending handle portion 48 which terminates in a thumb manipulating piece 49, which thumb piece is arranged adjacent to the handle 12 of the iron B so that the same can be readily pressed down to lift the needle valve off its seat. The adjacent handle bracket 50 can be provided with spaced teeth 51 and the lever 44 is adapted to be engaged by any one of said teeth so that the lever and consequently the needle valve can be held in adjusted position. When it is desired to move the valve off its seat the lever is pressed laterally, to disengage the same from the rack tooth and upwardly.

20 In the improved device, when it is desired to press and steam a garment, current is allowed to flow through both the iron B and the steam generating device C and upon heating of the block or body 19 the lever 44 is depressed so as to allow water to flow drop by drop from the valve body 30 into the chamber 38 where the same is converted into steam. This steam flows through the passageways 37, 38, 39 and 40 and then into the pipes 43 into the converging passageways 17 of the iron plate 11. The steam then leaves the iron through the ports 18 into the garment. The formation of the passageways 37, 38, 39 and 40 is such that the steam is superheated prior to the delivery thereof to the iron, so that a substantially dry steam will be furnished. In order to further superheat the steam the outlet ports 18 are spaced in the rear end of the iron, as heretofore stated, and these portions of the passageways 17 act in the nature of superheating portions for the steam.

40 When the iron is not in use the pet cock 36 can be closed and the current turned off. When it is desired to use the iron simply for pressing purposes the switch 27 can be manipulated so as to cut off the flow of current to the heating elements and the pet cock is left in a closed position.

50 In the foregoing description it can be seen that I have provided a novel portable steaming and pressing iron which can be easily operated by ordinary lay persons and which can be efficiently used for household purposes, if desired.

Changes in detail may be made without departing from the spirit or scope of the invention, but:

60 What I claim as new is:

1. The combination with a sad iron having longitudinally extending passageways and

- ports communicating with said passageways opening out through the lower face of the iron, of a steam generating device carried by said iron including a body having a steam generating chamber therein, a heat device surrounding said body, said body having a tortuous passageway communicating with said chamber, means for delivering a liquid to said chamber, and means for connecting the tortuous passageway with the passageways in said iron. 5
2. The combination with a sad iron having longitudinally extending passageways and ports communicating with said passageways opening through the lower face of the iron, of a steam generating device carried by the iron including a body having a steam generating chamber formed therein and a tortuous passageway communicating with said chamber, 15
- 20 a heating device surrounding the body, a liquid reservoir supported by said body in a plane above the same, a needle valve for controlling the flow of liquid from said reservoir into the chamber, and means connecting the tortuous passageway with the passageways in said iron.
3. The combination with a pressing iron having longitudinally extending passageways therein, and ports communicating with said passageways and opening out through the lower face of the iron, of a steam generating appliance mounted on the iron comprising a body having a steam generating chamber therein and a tortuous passageway communicating with said chamber, a portion of said tortuous passageway forming a liquid trap, a heating element surrounding said body, means connecting the tortuous passageway with the passageways in the iron, a water reservoir carried by said body, a needle valve for controlling the flow of water from the reservoir to said steam generating chamber, and means for manipulating said needle valve. 40
- 45 4. The combination with a pressing iron having passageways therein and ports communicating with said passageways and opening out through the lower face of the iron, of a steam generating device attached thereto comprising a body connected with said iron having a steam generating chamber therein, means connecting said steam generating chamber with the passageways in the iron, a heating element surrounding said body, a liquid reservoir carried by the body, a needle valve for controlling the flow of liquid from said reservoir to said steam generating chamber, a lever rockably mounted adjacent to its rear end on said body having pivotal connection at its extreme rear end with said needle valve, and a thumb manipulating piece on the forward end of said lever. 55
- 60 5. The combination with a pressing iron provided with a heating element and a sole plate, a manipulating handle and brackets connecting said handle with said body, one of said brackets being provided with a toothed rack, of a steam generating device carried by said iron including a block, said block having a steam generating chamber therein, means connecting said steam generating chamber with ports in said sole plate, a liquid reservoir carried by the block, a needle valve for controlling the flow of liquid from said reservoir into said chamber, a manipulating lever for said needle valve rockably mounted adjacent to its rear end on said block, and a pivotal connection between the extreme rear end of said lever and said needle valve, the forward end of the lever being arranged in the path of the teeth of the rack, and a manipulating thumb piece on the forward end of said lever. 70
- 75 6. The combination with a sad iron provided with an electric heating element, said sad iron having passageways therein and ports communicating with said passageways and opening out through the lower face of the iron, a block carried by said iron having a steam generating chamber therein and a tortuous passageway communicating with said chamber, means connecting the tortuous passageway with the passageways in the iron, an electric heating element arranged about said block, means for supplying electricity to the heating element of said iron and to the heating element surrounding the body, means for controlling the flow of electricity into the heating element of the block independent of the heating element in said iron, and means for supplying liquid drop by drop into the steam generating chamber. 80
- 85 90 95 100
- In testimony whereof I affix my signature.
